UNITED STATES PATENT OFFICE.

MARY E. LINDSEY, OF NEW ORLEANS, LOUISIANA.

UNSINKABLE SHIP.

1,264,311.

Specification of Letters Patent. Patented Apr. 30, 1918.

Application filed August 29, 1917. Serial No. 188,781.

To all whom it may concern:

Be it known that I, MARY E. LINDSEY, a citizen of the United States, residing at New Orleans, in the county of Orleans and State 5 of Louisiana, have invented certain new and useful Improvements in Unsinkable Ships; and I do hereby declare the following to be a full, clear, and exact description of the invention, such as will enable others 10 skilled in the art to which it appertains to make and use the same.

The invention relates to improvements in ships, more especially the means for protecting the same from torpedoes, mines and the 15 like.

The object of the present invention is to provide a simple, practical and efficient construction designed for use on both old and new vessels and capable of reducing to a 20 minimum the effect of a projectile, torpedo, mine or the like, and capable of enabling openings in a hull to be effectively closed temporarily for excluding the water from the interior of the vessel until there is an 25 opportunity for permanent repair.

With these and other objects in view, the invention consists in the construction and novel combination of parts hereinafter fully described, illustrated in the accompanying 30 drawings and pointed out in the claims here- to appended; it being understood that various changes in the form, proportion, size and minor details of construction, within the scope of the claims, may be resorted to 35 without departing from the spirit or sacrificing any of the advantages of the in- vention.

In the drawings:

Figure 1 is a vertical sectional view of a 40 portion of a vessel provided with a protecting structure constructed in accordance with this invention.

Fig. 2 is a similar view illustrating the manner of closing an opening.

Fig. 3 is a vertical sectional view of a portion of the vessel showing the construction applied to a new ship.

Fig. 4 is a horizontal sectional view taken substantially on the line 4—4 of Fig. 1.

Fig. 5 is a perspective view of a portion of one of the armor sections.

Fig. 6 is a sectional view of the same.

Like numerals of reference designate corresponding parts in the several figures of 55 the drawings.

Referring particularly to Figs. 1, 2 and

4, in which the construction is shown applied to an old vessel or ship after the same has been constructed and it is desired to protect the same, 1 designates the hull of 60 the vessel to which is applied in spaced relation thereto an outer shell 2 which may be constructed of any suitable material either wood or metal and which is spaced by ribs 3 similar to the ordinary construction of ribs of a ship. The hull 1 may be of either wood or metal and it is designed to be provided above a floor or deck 4 with suitable doors 5 adapted to afford access to the space between the inner and outer hulls. 70 The space between the inner and outer hulls below the deck 4, which is located above the water line, is divided by inner and outer walls 6 and 7 into outer intermediate and inner spaces 8, 9 and 10. The outer wall 6 75 may be constructed of any suitable material, preferably tongue and grooved wood or boards, to provide a water-tight wall which is connected at the lower edge with the inner wall 7 near the extreme bottom or keel of 80 the vessel. The space 9, which also receives the ribs 3, is designed to be filled with any suitable material such as tar and cinders, and the filling is designed to extend to a point above the water line, preferably adja- 85 cent to the deck 4.

The deck 4 is provided with doors 12 and 13 at the spaces 9 and 10 to afford access to the same. The intermediate space 9 between the inner and outer walls 6 and 7 90 receives armor sections 14 consisting of compressed cotton 15 maintained in a compressed condition by bands 16 and arranged within an outer cage or frame 17 of woven wire or netting, a covering or envelop 18 of 95 asbestos or other suitable material being interposed between the wire cage or frame. The bales or blocks constituting the armor sections are forced in the said intermediate space 9 and they may be of various sizes and 100 shapes and of a configuration to adapt them to entirely fill, or practically entirely fill, the space 9 at the areas where the hull is subjected to danger from projectiles, tor- pedoes, mines and the like. The doors 12 105 afford access to the spaces and are arranged at suitable intervals so as to enable jacks 19 of any desired construction either automatic or otherwise operable for compressing the armor sections within the intermediate space 110 9 to close up a hole and prevent ingress of water.

The inner wall 7, which is preferably constructed of metal, may of course be made of any suitable material, and the doors 13 are adapted to afford access to the space 10 to enable the inner hull to be temporarily repaired, which may be effected by any suitable means. When the construction is applied to new vessels, the inner hull 20 preferably extends only to the deck 4, the space 10 at the inner hull above the deck being open to the outer hull thereby increasing the capacity of this portion of the vessel. The rest of the construction is similar to that heretofore described and a detail explanation thereof is unnecessary. As the protective structure extends above the water line and to practically the keel of the vessel, an efficient protection against mines, torpedoes and the like is afforded and the vessel is rendered practically unsinkable.

What is claimed is:

1. A vessel of the class described including a hull and a walled space or compartment exteriorly of the hull, armor sections 25 consisting of bales of compressed cotton, and means for enabling the bales or sections to be compressed within the said space for closing an opening caused by a projectile.
2. A ship of the class described including 30 inner and outer hulls, said ship being provided between the inner and outer hulls with a space having openings at the top thereof, bales within said space, closures for the said openings, and means operable through the said openings for compressing the bales within the said space for closing an opening caused by a projectile.
3. A vessel of the class described including 35 inner and outer hulls, inner and outer walls arranged in the space between the inner and outer hulls and forming inner, outer and intermediate compartments, a top wall

located above the said walls and provided with doors for affording access to the inner and intermediate compartments, armor sections composed of bales of compressed fibrous material arranged in the intermediate space, and means operable exteriorly 45 of the said space for compressing the armor sections for closing an opening caused by a projectile.

4. A vessel of the class described including inner and outer hulls, inner and outer walls arranged in the space between the inner and outer hulls and forming inner, outer 55 and intermediate compartments, a top wall located above the said walls and provided with doors forming access to the inner and intermediate compartments, armor sections composed of bales of compressed fibrous material arranged in the intermediate space, and means located at the top of the intermediate 60 compartment for compressing the armor sections within the said intermediate space or compartment.

5. A ship of the class described including spaced inner and outer hulls, a deck located above the water line, said inner hull being provided at the deck with doors to afford access to the space between the hulls, 70 armor sections consisting of blocks of compressed fibrous material arranged in the space between the inner and outer hulls and located below the said deck, and means for compressing the armor sections within the 75 said space for closing an opening caused by a projectile.

In testimony whereof I affix my signature in presence of two witnesses.

MARY E. LINDSEY.
